UNITED STATES PATENT OFFICE.

JACOB FELBEL AND ANDREW W. STEIGER, OF NEW YORK, N. Y., AS-SIGNORS TO THE WRITING MACHINE MANUFACTURING COMPANY, OF SAME PLACE.

TYPE-WRITING MACHINE.

SPECIFICATION forming part of Letters Patent No. 400,200, dated March 26, 1889.

Application filed March 31, 1888. Serial No. 269,129. (No model.)

To all whom it may concern:

Be it known that we, JACOB FELBEL and ANDREW W. STEIGER, citizens of the United States, and residents of New York city, in the 5 county of New York and State of New York, have invented certain new and useful Improvements in Type-Writing Machines, of which the following is a specification.

Our invention relates more particularly to 10 type-writing machines wherein the type are impressed upon an inking-surface and caused to print directly upon the paper, and wherein a center guide is employed to direct all the type exactly to the same point, so that a perfect alignment in the printing may be obtained.

The invention has reference to a mode of 15 mounting the type bar or carrier; and it consists in pivoting it at one point to the free end of one pivoted link and at another point to the free end of another pivoted link, all as will be hereinafter more fully described, and set forth in the appended claims.

In the accompanying drawings, Figure 1 is 20 a longitudinal vertical section of a type-writing machine embodying our invention, many of the necessary parts of the machine—such as feeding and spacing mechanisms, &c.—being omitted to simplify the view. Fig. 2 is 25 a diagrammatical view of the type-carrier and its connections, and illustrating the movements of the type to and from the printing-point. Fig. 3 is a detail view of a modification.

30 In the several views the same parts will be found designated by the same letters of reference.

A is the base of the machine, at which are 35 pivoted key-levers B B, that are adapted to be operated in the usual way by finger-keys C C, connected thereto.

D represents (in dotted lines) the paper-platen or impression-roller. At the printing-point e of the machine is arranged a type-guide, E, adapted to receive each type and cause it to print always at the impression-point.

F is a type-carrier, preferably composed of a bar, f, having at one end a laterally-project-

ing arm, f', to carry the type G, and at the 50 other end a laterally-projecting arm, f'', bent in a direction opposite to the type-arm f'. The type-carrier is pivoted at K (at the junction of the bar f and arm f'') to one end of a link or lever, H, the other end of which is pivoted to the frame or some stationary part of the machine. Preferably we pivot all the 55 links or levers H at one end upon a wire ring, I, which is supported from the base or some other fixed portion of the machine. In the drawings we have represented the ring or pivotal bearing I as supported by arms i, branching from a pedestal or post, j, secured to the base-plate of the machine. The type-carrier is also pivoted at K' (at the rear end 60 of the arm f'') to one end of a link, L, whose opposite end is pivoted to the frame or some stationary part of the machine. By preference we pivot all the links L upon a wire ring, N, which may be supported by arms n n, projecting from the post or column j. The link 65 H is made to serve as the operating-lever by providing it with an arm or projection, h, on that side of its pivotal support opposite to the pivotal connection with the carrier F. To 70 this arm h is pivoted a connecting-rod, O, the lower end of which is attached to a key-lever, as customary heretofore.

We preferably arrange the parts so that 75 the type-arms f' will normally lie in a horizontal plane with their ends projecting radially of the printing-point e and resting above the pivotal bearings of the type-carrier; but the parts may be differently proportioned and otherwise arranged, so that the normal position of the type-carrier may be different from what we have shown and just above given our preference to.

P represents an inking-surface, so arranged 80 that when the carriers are in their normal positions the faces of the type will touch the same. This inking-surface may be a circular pad of felt, which may be supplied with ink in any desired manner. The fulcrum-ring N is arranged centrally of the machine and the 85 links L radiate outwardly and downwardly therefrom. The fulcrum ring or support I is arranged exteriorly and concentrically of the 90 95

fulcrum N, and the links H extend therefrom in radial lines inwardly and downwardly toward the links L. The inking-pad is arranged above the fulcrum-ring I and between the latter and the platen. The type stand above the links H and L and their pivotal supports or fulcrums and normally rest against the inking-pad.

The operation of the machine is as follows: Upon the depression of a key-lever, B, the rod O is drawn down and the lever H caused to turn on its bearing at I and swing upwardly. As the free end of the lever H begins to rise the free end of the link L begins to descend, and the type-carrier connecting the two is slightly elevated and turned. As the vibration of the lever H is continued the link L begins to ascend, being carried up by the arm f^2 , and the type-carrier, moving about the pivots K K^2 , is finally caused to take a quarter-turn, the type G traveling in the curved path marked x in the drawings. When the type shall have arrived at the line y a further movement of the lever will cause the carrier to move in a nearly vertical direction, as illustrated by the dotted line y, until the type G reaches the printing-point, and, passing through the guide, strikes against the paper on the platen or roller. Upon releasing the pressure on the finger-key the type-carrier returns through the same path to its normal position, and its type is caused to strike against the inking-surface and take a supply of ink for another impression.

A spring, R, may be provided at any suitable point to return the parts to their first positions.

By arranging the links to vibrate in opposite directions we are enabled to move the type in the shortest possible path to reach the printing-point, and thus secure rapidity of action. In moving to the printing-point each type takes two well-defined paths, being carried first in substantially a horizontal direction to a point opposite the printing-surface, and then in a direction substantially at right angles to its first path and perpendicular to the printing-surface.

By varying the proportions of the several parts and the relative locations of their pivotal points the track traversed by the type may be changed, and we therefore do not desire to be confined to the proportions and arrangements of parts shown.

If desired, the inking-pad may be dispensed with and the usual ribbon interposed between the platen and the face of the type. So, also, may the center guide be omitted; but the best results can be obtained by its employment.

Instead of the key-levers B and connecting-rods, some other connections may be provided between the finger-keys and the links H.

In lieu of providing the link H with an extension, h, and vibrating it by pulling down, as illustrated at Figs. 1 and 2, the connecting-rod may be attached to the link H in front of its pivotal support and the link vibrated

by an upward push, as shown in the modification exhibited at Fig. 3.

The gist of our invention rests in pivoting the type-carrier to the free ends of two links, as H and L, which vibrate in opposite directions. By this arrangement the type-face is turned while traveling to the printing-point, and then caused to move in a straight line and strike perpendicularly to the platen, whereby the impression upon the paper may be made without any liability of blurring. By this arrangement the type-face may also be presented perpendicularly to the inking pad or surface when used, and thus secure a uniform and perfect supply of ink.

In practice we have constructed and proportioned the parts substantially as shown, so that the type-face is given a quarter-turn and is presented perpendicularly to both the platen and the inking-pad, and the results have been most satisfactory as to the inking and printing mechanism.

By our invention a superior type-writing machine of small dimensions, light weight, and great durability and speed may be made at a very low cost.

What we claim as new, and desire to secure by Letters Patent, is—

1. In a type-writing machine, a type-carrier pivoted at one point to the free end of one pivoted link and at another point to the free end of another pivoted link, the said links being arranged to vibrate in opposite directions and cause the type to move in two well-defined paths, first in substantially a horizontal direction radially inward to the common center and then substantially in a straight line and axially to the printing-surface, substantially as shown and described.

2. In a type-writing machine, the combination of a centrally-arranged fulcrum-support, a series of links, L, radiating therefrom, a concentric and exteriorly-arranged fulcrum-support, another series of links, H, radiating therefrom toward the links L, and a series of type-carriers pivoted to said duplex series of radiating links H and L, substantially as set forth.

3. In a type-writing machine, the combination of a series of pivoted links, H, extending inwardly and downwardly, a series of links, L, pivoted nearer the center of the machine and extending outwardly and downwardly, and a series of type-carriers consisting of the arms $f f' f^2$, disposed as described, and pivoted to the free ends of the links H and L at the points $K K^2$, substantially as set forth.

4. In a type-writing machine, the combination of a series of inwardly-extending pivoted links, H, a platen above said links, a circular inking-surface above said links and between them and the platen, a series of outwardly-extending pivoted links, L, and a series of type-carriers, each pivoted at two points to the free ends of a pair of said links, H L, substantially as and for the purpose set forth.

5. In a type-writing machine, the combina-

tion, with an inking - surface, as P, and a
platen above the same, of the type-carrier F,
and the oppositely-arranged links H and L,
adapted to move the type from the inking-
5 surface, give it a quarter-turn, and then move
it to the platen, as set forth.

Signed at New York city, in the county of

New York and State of New York, this 17th
day of September, A. D. 1887.

JACOB FELBEL.

ANDREW W. STEIGER.
